H. MELLISH.

Grain Mill.

No. 11,558.

Patented Aug. 22, 1854.

UNITED STATES PATENT OFFICE.

HENRY MELLISH, OF WALPOLE, NEW HAMPSHIRE.

GRAIN-MILL.

Specification of Letters Patent No. 11,558, dated August 22, 1854.

To all whom it may concern:

Be it known that I, HENRY MELLISH, of Walpole, in the county of Cheshire and State of New Hampshire, have invented a new 5 and useful Improvement in Grain-Mills; and I hereby declare that the following is a full and exact description of the same, reference being had to the annexed drawings, in which the same letters refer to the 10 same parts in all the figures.

The nature of my invention consists in constructing on an arbor in a suitable stand; a bur for grinding by placing together a series of circular saws in a gang 15 with a circular steel or other metallic plate longer than the saws to serve as a finisher of the meal; and to the disk of the gang opposite to the finishing plate I attach a series of ring saws in a gang, which are kept apart 20 from the circular saws and from each other by washers on the bolts which confine the whole together. This bur is furnished with an adjustable case toothed on the surface fitting the periphery or grinding surface of 25 the bur.

Figure I is a perspective view of the mill. Fig. II is a perspective view of the end of the mill with its cap or front plate removed, showing the adjustable case in its curb, and 30 the cracker rest which projects into the area inclosed by the ring saws, and which with them constitute the cracker. Fig. III is the bur as if taken from its case and reversed so as to show its back disk with the 35 ring saws attached. Fig. IV is a longitudinal sectional view of the mill. Fig. V is the front plate to cover the bur, adjustable case, and curb. Fig. VI is the cracker rest for projecting into the area inclosed by 40 the ring saws.

A Fig. 1 is the bed piece with the puppets *a a*, with bearings and caps at their upper ends to hold the arbor I, from this bed piece also projects the puppet *b* and a correspond- 45 ing one on its opposite side which is not seen in the drawing.

C is the curb to contain and hold fast the adjustable case, and consists of a circular plate B, see Figs. I, II and IV having a 50 round hole through its center, see *h*, I, II, and IV, and a projection, from one of its disks seen at *c c c c*, Fig. II. These projections being connected by a continuation along the periphery of the plate as seen at 55 *i* Fig. II.

D D D D in Fig. II, are four gangs of

square or oblong plates packed into the curb C with one of their edges upon the disk of the plate B, and another hanging across the periphery of the curb *c* at right angles, 60 and made fast in their places with the set screws *e e e e*. See Fig. I and II, these gangs of plates forming the adjustable case, which is turned so as to form a true circle on its inner surface and cut with angling file 65 like teeth across the edges of the plates forming it, see F Fig. II. Around the inner circle and upon the front surface of the adjustable case D file like teeth are cut, see *g* Fig. II. The curb plate B is made fast to 70 the puppet *a* with the screw as seen at J Fig. IV, and in like manner to the puppets *b*, Fig. I.

Fig. III is the bur constructed by placing together on the arbor I a series of circular 75 saws, see *k* Fig. III and IV, to the front disk of this gang of saws is attached a finishing plate larger than the saws, that portion of the disk of this plate *m* Figs. III, and IV, which extends beyond the periphery 80 of the saws is furnished with teeth like file teeth see *m* Fig. III. To the other disk of this bur are attached a series of ring saws made thicker at their inner than at their 85 outer edges, see *n* Figs. III and IV; these ring saws are kept a little distance apart and from the gang of plates forming the bur by washers *o* between them, see Fig. IV, the whole being confined together with the screw bolts *P* see Figs. III and IV, this bur is 90 confined on the arbor *l* in its case with the screw nut *P* see Fig. IV, *r* Figs. II and IV is a cracker rest fitting on to the puppet *a* and into the spaces between the puppet *a* and the puppets *b b* on the front of the bed 95 piece A, and is made fast to the puppet *a* with the screw *s* see Fig. VI with a portion of it projecting and nearly filling the lower half of the area of the inner circle of the ring saws, see *r* Fig. IV. *t* in Fig. II is a 100 slotted plate made fast to the cracker rest *r* with the screw *u*, which plate should be confined close to points of the teeth on the inner circle of the ring saws, to prevent the grain from passing without being cracked. 105

Fig. V is a dishing cap on front plate with a lip *v* see Fig. IV to fit the neck *w* of the curb C, see Fig. IV. This cap is made dishing so as to form a space X see Fig. IV about the finishing plate *m* so as to 110 admit of the discharge of the meal through the opening *y* in the front plate Fig. V, see

y, Fig. IV. This front plate is made fast to the curb *C* with screws through the holes *z z z z*, in the plate Fig. V, and into the holes *z z z z* in the curb *C*, Fig. II, the plate 5 in its place *v* Fig. I and IV, where its fastenings do not show.

a¹ Fig. I is the hopper in the form represented in the figure, and is made fast to the curb *B* with the screws *b²*, see Fig. 10 I, and a corresponding one not seen in the figure, its lower end is confined to the cracker rest *r* with the screws *c²*, see Fig. II. *d²* is a section of the curb which may be removed by taking out the screws *e²* which 15 confine it, for the purpose of filing the saws when required.

F Figs. I and IV is a regulating screw, and G a friction plate.

Operation: Having made the mill fast to 20 some firm support by bolts through the holes *E* in the bed piece *A* and corresponding ones in its opposite side, and applying power by means of a belt over the pulley *H*, and giving it the necessary revolving motion, and 25 the grain being fed into the hopper by any of the ordinary means made use of to feed grain into grain mills, it will be seen that the grain will pass down upon the cracker rest in the area of the ring saws when it 30 will be caught by the teeth on the inner edges of the ring saws, cracked and passed through the spaces between them and to the grinding surfaces of the case and bur, and between them by the oblique direction of the 35 teeth of the bur and case, and finishing plate, where the requisite degree of fineness is given to the meal by turning the thumb *F* against the friction plate *G*, see Fig. IV, by which means it will be seen that the 40 arbor *I* will be slipped in its bearings and the finishing plate *m* will be moved back from the grinding surface of the adjustable case; so that by turning the screw one way or the other the meal may be made 45 finer or coarser as may be required. It should here be remembered that the oblique direction of the teeth of the bur and case always when grinding causes the finishing plate to bear against the front of the 50 adjustable case unless prevented with the screw *F*. And I will also state that the bur made of circular saws in combination with the adjustable case without the ring saws may be so adjusted as to grind shelled grain,

but not so fast and well with the same 55 amount of power and for the purpose of grinding ears of corn in the above described mill the ring saws are absolutely indispensable, and therefore as a general grain grinder the mill would be incomplete without them. 60

To adjust the case to the bur the front plate or cup should be removed, the bur taken from the arbor, and one or more thicknesses of paper wound around the periphery of the plates constituting the bur; when it should be replaced on the arbor; the set screws *e* loosened and the plates constituting the adjustable case *D* slipped up to the paper on the bur, and made fast with 70 the set screws, when the bur should be taken out of the case, the paper removed, and the bur and front plate confined in their places.

Claims:

1. I claim as my invention the arrangement of the ring saws *n*, as set apart by the washers *o* on the bolts *P* with the cracker rest *r* inclosed by them in combination with the adjustable case *D* or its equivalent, for the purpose of cracking ears of corn and 75 also shelled grain that it may be the more readily received between the bur *k* and the grinding surface of the adjustable case *D*, and for the further purpose, by the oblique direction of the teeth on the outer edges of 80 the ring saws and that of the teeth on the inner surface of the adjustable case *D* of forcing the cracked grain into the space between the periphery of the bur *k* and the 85 grinding surface of the adjustable case *D*. 90

2. I also claim the arrangement of the bur *k* constructed as above described in combination with the finishing plate *m* and the adjustable case *D* or its equivalent, operating as the bur does conjointly with the ring 95 saws *n* inside the adjustable case *D*, and the toothed disk of the finishing plate *m* against the front surface of the adjustable case *D*, for the purpose of further grinding the required degree of fineness to the meal 100 as it passes between them, the whole being arranged, combined, and operating conjointly substantially in the manner and for the purpose above described.

HENRY MELLISH.
